(No Model.)

E. BOEING.
FILTER.

No. 468,984.

Patented Feb. 16, 1892.

UNITED STATES PATENT OFFICE.

ERNST BOEING, OF BAD NAUHEIM, GERMANY.

FILTER.

SPECIFICATION forming part of Letters Patent No. 468,984, dated February 16, 1892.

Application filed May 13, 1890. Serial No. 351,701. (No model.)

To all whom it may concern:

Be it known that I, ERNST BOEING, a subject of the King of Prussia, residing at Bad Nauheim, in the Grand Duchy of Hesse Darmstadt, in the German Empire, have invented certain new and useful Improvements in Water-Purifying Apparatus; and I do hereby declare the following to be a full, clear, and exact description of the invention, such as will enable others skilled in the art to which it appertains to make and use the same.

My invention is an improvement in water-purifying apparatus; and it consists in the novel features hereinafter fully described.

15 In the accompanying drawings I have shown a sectional view of a water-purifying apparatus constructed in accordance with my invention, and said invention is fully disclosed in the following description and claims.

20 The novelty of this invention consists in having between the supply-pipes and the boiler an apparatus in the nature of a feed-water heater, which mechanically purifies the water completely and then lets it pass to the boiler. This apparatus is made of sufficiently 25 strong iron and has generally the form of a cylinder. The usual size of the apparatus is 1.25 meters in height and fifty centimeters in diameter. Such an apparatus will be sufficient 30 for one to four boilers; but the same can be greater or larger, according to requirements.

The iron cylinder of the apparatus consists of two parts, of which the under part is as a rule 1.00 meter high and the upper part A 35 twenty-five centimeters high. These two parts are fastened together by means of screws passing through flanges; but before fastening the parts together a strainer D, made of sheet-copper or of sheet-iron, is laid in and this 40 separates the two parts. This strainer D is provided with openings five millimeters wide, (strainer-holes.) The under part of the cylinder has about five to ten centimeters above the bottom a man-hole, which is really an 45 easily-to-be-closed opening and is for the purpose of removing any sediment. The supply of water, which is effected by means of one or more pipes and by means of steam-pumps, pulsometers, injectors, &c., any one or more 50 acting alone or together, opens about forty centimeters above the bottom of the lower part of the cylinder. The pipes which carry

the water into the steam-boiler open above into the upper part of the cylinder at least fifteen centimeters above the sieve-partition, 55 strainer, or filtering-partition. Between the apparatus and the steam-boiler there is a shut-off valve a. Between the apparatus and the pumps, injectors, &c., there is close to the apparatus a shut-off valve b and on this a 60 check-valve.

In the upper part of the apparatus, upon the filtering-partition, there is a layer, about ten centimeters high, of smooth quartz stone 65 of six to ten millimeters in thickness.

In the under part of the apparatus there is a so-called "floating layer" ten to fifteen centimeters high. This floating layer consists of small cubes six to ten millimeters in size, which are made of suitable wood, such as willow or walnut. There must be so many of 70 these cubes filled in as that when the apparatus is filled with water the floating layer under the sieve-partition will be ten to fifteen centimeters thick.

The procedure in the apparatus, then, for the perfect purification of water is as follows: If water is to be passed through, the shut-off valve a, between the steam-boiler and the apparatus, is opened, so that hot water from the 80 boiler will pass into the upper part of the apparatus, and after passing through the quartz layer, as pumice-stone, filtering-stone, &c., will pass into the lower part. Then the shut-off valve b, between the apparatus and the 85 pump, injector, or the like, is opened and the passage proceeds. The water thus brought forward now flows into the lower part of the apparatus and passes upward through the floating layer and through the quartz layer 90 on the filtering-partition into the upper part of the apparatus, and from there into the steam-boiler by reason of the pressure which is produced by the pump, injector, or the like. The floating layer of wooden cubes takes all 95 the slime of the water, but purifies itself constantly of this, because the separate parts as soon as they are sufficiently covered with slime sink, and there are met by the inflowing stream of water, whereby they are readily freed from slime and then pass upward. If very fine particles of slime are carried onward by the water, these will be caught by and remain in the quartz layer, which again 100

filters the water. This quartz layer is made of thickness according to the quantity of slime held by the water, so that there may be a perfect filtration and purification. The particles of slime which are caught and held by the quartz layer are at each induction by the streaming back of hot water, which establishes the equilibrium between the boiler and the apparatus, carried back through the sieve-partition, here taken up by the wooden cubes, and thus carried to the bottom of the apparatus. If the steam-boiler to be fed has a greater quantity of salts, alkalies, &c., which ought to be removed, then there may be placed directly upon the sieve-partition under the quartz layer suitable substances between layers of raw cotton, &c. In place of the layer of quartz there may be any other rough pieces of pumice-stone, filtering-stone, or the like, and the upper part of the apparatus may be so arranged that it may be easily opened and in a few minutes be purified even during operation.

Steam-boilers which heretofore have had to be cleaned every few months can be used by this apparatus for years and even at the end of this time no scale will be found.

This apparatus can be put up at small cost and may be used for years without necessity of resupply of filtering material. It is sufficient, as a rule, if the upper filling is taken out of the apparatus once a year, washed clean, and replaced.

The apparatus may itself be cleaned during operation as soon as the shut-off valves *a* and *b* are closed. By means of a small purge-valve (not shown) not forming any part of this invention the pressure and the water are first let off and then the man-hole *C* at the

under part of the apparatus is opened and the slime, as well as the floating layer, is taken out. The last is then washed in water and filled into the clean apparatus, which may then at once be put into use.

The whole cleaning of the apparatus requires but a few minutes and may be performed without difficulty.

Having thus fully described my invention, what I claim as new, and desire to secure by Letters Patent, is—

1. A water-purifying apparatus consisting of a vessel having an inlet near the bottom and an outlet connected with said vessel near the top of the same, said vessel being provided with floating filtering material, and a pervious partition between said floating material and the outlet, substantially as described.

2. A water-purifying apparatus consisting of a vessel provided with an inlet near the bottom and an outlet near the top of the same, a stratum of filtering material forming a partition between the said inlet and outlet and floating filtering material below the said partition, substantially as described.

3. A water-purifying apparatus consisting of a vessel provided with an inlet near the bottom and an outlet near the top, a pervious partition between said inlet and outlet, filtering material above said partition, and wooden cubes floating in and across the vessel below said partition, substantially as described.

In witness whereof I have hereunto set my hand in presence of two witnesses.

ERNST BOEING.
